(57) **CLAIM**

The ornamental design for a linear luminaire, as shown and described.

DESCRIPTION

FIG. 1 is a perspective view of a linear luminaire, illustrating our new design;

FIG. 2 is a left elevational view of the linear luminaire;

FIG. 3 is a right elevational view of the linear luminaire;

FIG. 4 is a front elevational view of the linear luminaire;

FIG. 5 is a back elevational view of the linear luminaire;

FIG. 6 is a top plan view of the linear luminaire; and,

FIG. 7 is a bottom plan view of the linear luminaire.

The unshaded portion enclosed by broken lines in FIGS. 1 and 2 forms no part of the claim. Additionally, the unshaded structure illustrated in broken lines is environmental structure that also forms no part of the claim.
